UNITED STATES PATENT OFFICE.

WILLIAM M. MADISON, OF CLEVELAND, OHIO.

DESIGN FOR AN ADVERTISING AND TOY BALLOON.

56,073.

Specification for Design.

Patented Aug. 10, 1920.

Application filed March 26, 1918. Serial No. 224,906. Term of patent 14 years.

To all whom it may concern:

Be it known that I, WILLIAM M. MADISON, a citizen of the United States, residing at Cleveland, in the county of Cuyahoga and State of Ohio, have invented a new, original, and ornamental Design for Advertising and Toy Balloons, of which the following is a specification, reference being had to the accompanying drawing, forming part thereof.

The figure is a perspective view, showing my improved design.

I claim:

The ornamental design for an advertising and toy balloon, as shown.

In testimony whereof I affix my signature.

WILLIAM M. MADISON.
